SELECTIVE EJECTOR MECHANISM

Carl E. Ekdahl, Worcester, Mass., assignor to
Harrington & Richardson Arms Company,
Worcester, Mass., a corporation of Massachusetts

Application May 9, 1940, Serial No. 334,176

6 Claims.

(Cl. 42—47)

This invention relates to automatic selective spent-shell ejectors, particularly but not necessarily, applicable to multiple barrel shotguns.

Objects of the invention include the provision of a firearm having automatic means to eject the spent shell upon opening the gun; the provision of means located entirely in the frame and barrel lug for ejecting a fired shell while retaining a loaded shell in the barrel; the provision of means automatically set by opening the gun to cock the firing pins and set the ejector mechanism; the provision of an automatic ejector for shotguns wherein the firing pins are operatively associated with the ejectors in such a manner as to set the latter in shell-ejecting position upon firing the shell or releasing the pin; the provision of latches for the ejectors, said latches being set in position for permitting ejecting of any shells fired, by the action of the firing pins in firing such shells; the provision of a trigger actuated firing pin having a linkage with a cocking rod to move the latter, upon firing a shell, to latch the corresponding ejector, locking the same against movement until such time as the gun shall have been opened a predetermined amount; and the provision of spring means compressed by the opening of the gun, means to release said latch and spring means to thereby eject the spent shell upon further opening of the gun; and means for resetting said ejecting means, cocking rods, firing pins, etc., upon said opening.

Other objects and advantages of the invention will appear hereinafter.

Reference is to be had to the accompanying drawings, in which

Fig. 1 is a view in elevation of a gun embodying the invention, with parts broken away;

Fig. 2 is a section on line 2—2 of Fig. 1;

Fig. 3 is a section on line 3—3 of Fig. 1;

Fig. 4 is a detail view looking in the direction of arrow 4 in Fig. 1;

Fig. 5 is a detail plan view of one end of the cocking rods;

Fig. 6 is a side elevation with parts in section of one of the ejectors;

Fig. 7 is a view looking in the direction of arrow 7 in Fig. 6;

Fig. 8 is a bottom plan view of the ejector latches;

Fig. 9 is a sectional view showing a cocking rod and its operating means;

Fig. 10 is a view of the breech lock looking in the direction of arrow 10 in Fig. 9; and

Fig. 11 is an exploded view of the lug and frame.

The numerals 10, 12 indicate the left and right barrels respectively of a double-barrel shotgun, which is selected as a medium for the disclosure of the present invention. The stock of the gun is not shown as it forms no part of the invention, but in practice, a stock would be fitted over and secured to the frame, indicated generally at 14, concealing the firing mechanism shown in elevation in Fig. 1.

The forend wood is indicated at 16, and the forend iron at 18, the forend being detachably secured to the barrels by any conventional means such as a spring catch. The forend iron is provided with a rear concave portion as is usual, to cooperate with an opposed but smaller concavity 20 in the lug 22, the latter being attached to or integral with the underside of the barrels adjacent the breech. The concavity 20 in the lug forms a semi-cylindrical hollow for the pivotal reception of a correspondingly shaped pin 24 at the forward end of the frame 14, this pin being inserted in and forming a part of the frame forward end 26 which is rounded off at 28 to pivotally slide within the concave portion of the forend iron. Thus, the frame 14 being applied to the lug by the pin 24, and the forend then latched in place, the gun can be opened by pivoting the frame about the axis of pin 24, the forend iron and lug cooperating to prevent detachment of the frame from the barrels, and limiting the movement of the frame 14 to a pivotal movement.

Frame 14, besides its forward part 26, includes breech portion 30 forming a frame line 32 with the breech end of the barrels, and a central post 34. Left and right firing pins 36, 36' are slidably received in bores 38 in the portion 30, these bores stopping short of the breech line, and being connected thereto by smaller bores 40 accommodating the points 42 of the firing pins. At the ends remote from the points 42, the firing pins are squared in cross-section and are arranged to be slidably guided in slots 44 in the post 34. Coil springs 46, 46' surround the pins and bear at one end against the post and at the other end against collars 48 fixed to the pins, and it will be seen that these springs continuously urge the firing pins to firing position.

Sears 50, 50' are pivoted as at 52 in post 34 in an interior slot, and these sears are provided with sharp shoulders 54 at their rear ends. Each firing pin 36, 36' is provided with a notch 56 corresponding to the shoulders 54. The rear ends

of the sears are separately urged towards the firing pins by individual sear springs 58, each of which bears at one end on its trigger rod 60, 60', respectively. The forward ends of the sears are urged by the springs towards their corresponding trigger rods in front of post 34, and bear thereagainst. The trigger rods and triggers are pivoted at 62 to the frame 14. The gun is cocked in Fig. 1, and the sear shoulders are shown engaged in the notches 56, thus locking the firing pins against forward movement to firing position.

Two cocking levers 64, 64' are pivoted in the frame 14 at 66, although they may be pivoted on the trigger pivot 62. These levers are provided at their free ends with enlarged bosses 68 which ride in slots 70 in the collars 48, and clearly any movement of a firing pin is transmitted to its cocking lever and vice versa. Intermediate its ends, each cocking lever passes through a slot 72 adjacent the rear end of each of the separate cocking rods 74, 74', these rods being slidably mounted in the breech portion 30 of frame 14 and extending forwardly through the portion 26, and protruding through the end of said portion 26 into a cut away cavity 76 in the concave face of the forend iron 18. This cavity provides a rearwardly and upwardly sloping cam face 77. The shoulders 78 forming slots 72 engage either side of the cocking levers, so that any movement of the latter is communicated to the rods, and vice versa. With the gun cocked, as in Fig. 1, the cocking rods are in retracted position as shown in that figure.

The forward portion 26 of the frame 14 is provided with a hollow chamber 80, through which the cocking rods pass, this chamber being defined by the frame line face at 32, the inner side walls of the chamber, and flanges 82. These flanges are cut away as at 84, for a purpose to be described. In the portion of the cocking rods passing through chamber 80, the faces of the rods are partially cut away to form like cam surfaces 86.

Referring to Figs. 6 and 8, it will be seen that the lug 22 is made up of a plurality of spaced parallel plates 22', these plates being integral with or fixed to the barrels. This arrangement leaves two spaces, one each between the central plate and an outer plate. A pin 88 extends through the three plates and pivotally supports the ejector latches 90, 90' in the above-mentioned spaces. These latches are of the shape shown and each has a laterally outwardly extending releasing lug 92, 92'. A friction spring 94 engages the inner faces of the latches and prevents free pivoting thereof, so that the latches will always remain where placed. Each latch has a cam surface 96, 96' at its end opposite the pivot, and a projection 98 on the edge opposite the lugs 92, 92'.

Extending forwardly from and guided in ways in the lug 22 are a pair of slidable ejector plungers 100, 100'. Each plunger is provided with an end coil spring 102 at its rear end, and these springs also bear on the forward ends of a pair of ejectors 104, 104'. Each of these ejectors has a catch 106' cooperating with its corresponding projection 98. The forward portion 26 of frame 14 terminates in an extending lip 106 having a cam surface 108 against which the ends of the ejector plungers bear by action of springs 102. Although when the gun is closed, this engagement is light, as the springs are not compressed but very slightly, still the opening of the gun forces the plungers back against the action of the springs, and thus

creates a friction binding against the cam surface 108.

The top lever 110 is operatively connected as for instance by a cam 112 (Fig. 10) to a locking bolt 114 which locks the gun in closed position by its extension into depression 115 in the lug 22. Extending rearwardly from the bolt are two arms 116, slidably mounted in the breech portion 30 and protruding rearwardly therefrom at each side of the cocking levers 64, 64'. Shoulders 118 in the arms 116 engage the cocking levers in their rearward travel when the top lever is actuated, and force these levers backwardly far enough to release the points 42 from the shells so that the gun may then be opened. It is to be noted that the rear end of lug 22 is provided with a cam surface 120 so that when closing the gun, the bolt 114 will ride up this cam and snap into depression 115, thus avoiding the necessity of operating the top lever.

After the ejector plungers, ejectors, and ejector latches have been assembled in the lug 22, and the locking rods, levers, firing pins, and sears have been assembled in the frame 14, the latter is secured to the lug as illustrated in Fig. 11. The portion 26 of the frame is placed in position wherein the pin 24 is in advance of its final location in cavity 20, and the lug 22 is brought down so that the releasing lugs 92, 92', on the ejector latches, pass through the cut away portions 84 in the flanges 82. Then the barrel is moved forwardly, or the frame 14 rearwardly, until the pin 24 is in position to seat in the cavity 20, and the top lever is actuated to withdraw the bolt 114. The frame 14 is then pivoted toward the barrel and the breech closed. The forend is then secured in place as usual, and the frame is thus secured to the barrel, as pin 24 cannot escape from cavity 20 and the curved face 28 of the forward portion 26 of the frame is locked by the pin 24 against the concave portion in the forend iron.

In this position, the releasing lugs 92, 92' are trapped within chamber 80, and will bear upon the flanges 82 when the gun is opened, to assist in stopping the opening action at a predetermined point, and to achieve other results to be described. Also, the cams 96, 96' project into the depressions in the cocking rods 74, 74' forming the cam surfaces 86.

In the operation of the device, assuming the parts to be in position as shown in Fig. 1, the firing pins 36, 36' are cocked, and two loaded shells are in the breech. If the trigger connected to arm 60 is pressed, it will swing the arm up about pivot 62, thus pivoting sear 50 clockwise about pin 52, against the action of its spring 58. This releases shoulder 54 from notch 56, and loaded spring 46 is then free to snap the firing pin forward, the point 42 projecting slightly beyond the frame line 32 to fire the shell in the left hand barrel. Assuming that the other barrel is not fired, the operator desires to reload the fired barrel so as to have two shots ready for the next opportunity.

As the firing pin 36 snaps forward, it moves the cocking lever 64, the latter pivoting about its pin 66, and in turn, the cocking lever forces the cocking rod 74 forwardly, so that its front end projects further into the cavity at 76 and approaches closely to cam face 77. Of course, spring 46 will hold the parts in this position.

In its forward movement, the cocking rod 74 cam surface 86 engages the cam 96 and thereby urges the ejector latch 90 upwards about pivot

88, as seen in Fig. 6, so as to engage projection 98 into the catch 106' in the ejector 104. This locks the ejector in place, due to the friction spring 94, which ensures that the latch 90 will stay in position. Of course, the latch 90' has not been moved, since cocking rod 74' has not been urged forward, as long as trigger arm 60' has not been actuated, and therefore the ejector 104' is not latched under the conditions above assumed.

The top lever 110 is now pivoted to withdraw bolt 114 from its locking position in depression 115 in the lug 22, and as the bolt retreats, one of the shoulders 118 engages the lever 64 and starts to pivot it against the tension of spring 46 and thus withdraws point 42 from the cap in the exploded shell so that the frame 14 may be pivoted to open the gun. As this occurs, cam face 108 impinges on the ends of ejector plungers 100, 100', and urges the same in a rearward direction. This action tensions the springs 102, and as ejector 104' is not latched, it is relatively slowly urged rearwardly to project the unfired shell slightly from the breech, but this does not of course eject the shell.

On the other hand, as plunger 100 is urged rearwardly by the cam 108, it tensions its spring 102 to a large degree, since ejector 104 is latched, and cannot be moved. As the frame 14 is further pivoted, however, it will be seen that releasing lug 92 engages its adjacent flange 82 on the fore portion 26 of the frame, and this occurs prior to engagement of lug 92' with its flange, since the latch 90 is in its upward location while latch 90' is still in its lowermost position. The engagement of lug 92 with the flange pulls the latch 90 downwards, thus releasing the ejector 104 and allowing its spring 102 to snap it rearwardly and forcibly throw out the shell. Further movement of frame 14 is inhibited by the lugs 92, 92'.

Of course, if both shells have been fired, they will both be thrown out at the same time, and if neither has been fired, they will be moved out slightly but not ejected. Thus it will be apparent that a completely automatic, selective ejector for fired shells in multi-barreled guns has been provided, and its action does not depend on any preselector or upon any action or thought taken by the operator other than to load, cock, and shoot.

While the gun is in the act of being opened, the end of a cocking rod which has been advanced, by firing, into substantial contact with cam 77, in effect slides up the cam. As the cam slopes rearwardly, the rod is also forced rearwardly, and of course carries its lever 64 or 64', as the case may be, and its firing pin, backwardly against the tension of the firing pin spring. At the time when the fired shell or shells are ejected, the notch 56 will engage shoulder 54 on the sear, and the firing pin is again cocked.

Further, as the gun is closed, the friction between cam 108 and the spring loaded plungers 100, 100' is decreased to practically nothing, so that near the end of the closing action, the force needed to finish closing the gun becomes very small and this gives it the effect of snapping shut, particularly with the influence of bolt 114 sliding on the lower inclined portion of depression 115 in the lug 22. The top lever and hence the bolt 114 are continuously urged to locking position by any convenient spring mechanism, such as the spring indicated at 125, which may be connected to the parts in any desired or suitable manner.

Having thus described my invention and the advantages thereof, I do not wish to be limited to the details herein disclosed, otherwise than as set forth in the claims, but what I claim is:

- 5 1. In a device of the class described, a firearm having a barrel and a pivoted frame, an ejector and normally inoperative latching means therefor on the barrel, a firing mechanism and a cocking rod on said frame, said rod being movable by said firing mechanism in the latter's movement to firing position, means on said rod to engage said latching means with said ejector during such movement, spring means to spring-press said ejector and means to release said latching means upon pivoting said frame, means secured to the barrel to reposition said cocking rod and thereby cock said firing mechanism upon said pivoting of the frame, and means on said frame effective to compress said spring means just prior to the operation of said releasing means during the frame pivoting action.
- 10 2. In a device of the class described, a gun barrel having a lug, a shell ejector slidably mounted in association with said barrel, spring means for urging said ejector towards ejecting position, a latch located within said lug and adapted to engage said ejector to hold it against the spring action, a frame pivoted to said barrel and mounting a firing mechanism therein, a lever operatively connected to said mechanism, a cocking rod in said frame operatively connected to said lever, said rod having means adapted to move the latch into ejector-locking position upon actuation of said lever by said firing mechanism, when the latter is moved into firing position; means on the frame to compress said spring means upon initial pivoted movement of the frame, and means on said frame to release said latch upon pivoting of said frame relative to said barrel and lug to breech open position.
- 15 3. A firearm having a barrel and a frame pivoted with respect thereto, a lug on said barrel, firing mechanism in said frame, means to cock said firing mechanism, said means being movable in one direction by said mechanism upon firing thereof and movable in the opposite direction to cock the latter, means to move said cocking means in said opposite direction, a shell ejector, a spring to operate the ejector, means on said lug to latch said ejector against the actuation of the spring, said latching means being movable out of ejector-latching position to release the spring, said cocking means having means to move said latch into said position upon movement of said cocking means in said one direction, means on said frame to move said latching means out of said position upon pivoting of said frame to breech opened position relative to said barrel, and means on the frame to compress the spring upon initial pivoting of said frame towards breech open position prior to the removal of the latching means from ejector-latching position, whereby the spring is compressed in preparation for operating the ejector.
- 20 4. A firearm having a barrel, a frame pivoted to said barrel, firing mechanism in said frame, a cocking rod associated with said firing mechanism to be moved thereby, a movable latch on said barrel, an ejector on said barrel, an ejector plunger associated with said ejector, a spring between said ejector and plunger, means on the ejector to receive said latch to lock the ejector against ejecting movement, means on said cocking rod to move said latch to ejector locking position upon actuation of said firing mechanism,
- 25
- 30
- 35
- 40
- 45
- 50
- 55
- 60

means on the frame for engaging and moving said plunger to compress said spring upon initial pivoting movement of said frame when said latch is engaged with said ejector, means on said latch adapted to engage said frame upon further pivoting movement thereof to release the latch from the ejector whereby said spring is released to eject a fired shell, said spring being stiff enough to act as a link between the plunger and ejector so that the latter is moved towards ejecting position when the frame is pivoted to open position and the latch is not in ejector locking position.

5. A firearm comprising a barrel, a frame pivoted to the barrel for opening the breech, firing mechanism on the frame, a cocking rod associated with the firing mechanism for movement therewith, an ejector slidably mounted on the barrel, an ejector plunger aligned with the ejector, a spring located between the ejector and

10
15
20

plunger, means on the frame adapted upon pivoting movement of said frame to engage the plunger and compress the spring against the ejector when the latter is locked against ejecting movement and to move the ejector towards ejecting position when the ejector is not so locked, and means to lock the ejector upon actuation of the firing mechanism, said locking means comprising a movable latch, cooperating means on the latch and cocking rod for moving the latch to ejector-locking position upon movement of the cocking rod under influence of the firing mechanism, and means to release the ejector from the latch, whereby the ejector will be snapped by the spring to ejecting position to eject a fired shell only.

6. A firearm as recited in claim 5 wherein said releasing means comprises a flange on the latch and a corresponding flange on the frame, said latch being mounted on the barrel.

CARL E. EKDAHL.
